UNITED STATES PATENT OFFICE

ARTHUR F. COOK, OF HAVERHILL, MASSACHUSETTS, ASSIGNOR TO UNITED SHOE MACHINERY CORPORATION, OF PATERSON, NEW JERSEY, A CORPORATION OF NEW JERSEY

METHOD OF MAKING WOOD HEELS

Application filed May 21, 1928. Serial No. 279,453.

This invention relates to the making of wood heels.

In the making of wood heels as heretofore practised the first operation performed on 5 the heel blank (which is in the form of a trapezoidal prism, the sides of the heel being formed from the end faces of the prism) has been grooving, or cutting the breast curve. The groove thus cut is horizontal in the case 10 of Louis heels and vertical in the case of Cuban heels. In the grooving of a Cuban heel blank the blank has been gaged from the side, and in the grooving of a Louis heel blank the blank has been gaged from the 15 heel seat surface. The next operation has been the turning or shaping of the sides and back of the heel, and inasmuch as the cutter cuts away the flat sides and back of the heel blank, the gaging has been done from the 20 already finished breast only, and there was no insurance of proper lateral positioning of the blank, such positioning depending 25 solely on the operator's skill. In the case of Cuban heels, especially, in which the breast groove is vertical, a slight lateral error in position might place the lateral surface cut in the turning operation in hopelessly wrong relation to the breast curve.

The next operation has been concaving, or 30 cutting the cup-shaped heel-seat-receiving surface at the upper end of the heel blank, the blank being held in a Babbitt metal mold or chuck made to fit the contour of the lateral and rear faces of the heel. Such molds are 35 expensive and troublesome and often inaccurate, and the results of this operation have been unsatisfactory. For example, the flat rim around the upper surface of the heel where it intersects the lateral and rear faces 40 has often been of uneven width, due to the imperfection of the gaging apparatus.

In short, it has heretofore been difficult to form these three principal surfaces of the heel in proper relation to one another, due 45 to the fact that there is no definite relation between the respective gaging operations which precede their formation, the breast groove being gaged from the side or heel seat surface of the blank, the lateral surface being 50 gaged from the groove, and the cup or heel

seat surface being gaged from the lateral surface.

The present invention avoids these difficulties by providing for gaging each of the three operations referred to from a flat lateral surface of the blank, and preferably gaging all three from the same flat lateral surface, so that the surfaces formed in these operations can be formed in definite predetermined relations to one another. This is 60 accomplished, in accordance with this invention, by interchanging the order of these three operations, the turning operation being last, the flat lateral surfaces of the blank being preserved throughout the other two 65 operations, and each of the three operations being gaged from a flat lateral surface of the blank.

The invention will be understood from the following description taken in connection 70 with the accompanying drawings, in which

Fig. 1 shows a heel blank as it exists prior to any of the three forming operations discussed;

Fig. 2 illustrates the grooving operation as 75 performed on a Cuban heel blank;

Fig. 3 illustrates the grooved Cuban heel blank;

Fig. 4 illustrates the concaving operation on the blank shown in Fig. 3;

Fig. 5 illustrates the concaved blank;

Fig. 6 illustrates the turning operation as performed on the blank shown in Fig. 5;

Fig. 7 is a perspective detail of the machine shown in Fig. 6; and

Fig. 8 illustrates the turned blank.

The illustrated wood heel blank (Fig. 1) is of trapezoidal prismatic form, the trapezoids A B F E and D C G H forming the ends of the prism and the other faces being 90 rectangular. The breast of the heel is formed from the face A B C D, the heel seat surface from the face B F G C and the lateral surfaces (the sides and back) from the faces A E F B, D H G C and E F G H. In the 95 case of Louis heels the breast groove is an irregular cylindrical surface with its elements parallel to the edges B C, A D; in the case of Cuban heels the breast groove is a substantially circular cylindrical surface 100

with its elements substantially parallel to the lines A B, D C (Fig. 3). In the case of the Louis heel grooved as above described, a certain latitude is permissible in the sidewise location of the heel seat and lateral surfaces provided they themselves are properly located relatively to each other, and gaging the Louis heel blank from the side in the grooving operation is therefore not so important. But if the shank lip of the Louis heel blank is curved before the turning operation, it is necessary that the side surfaces be centered with the curved lip, and gaging from a side face A E F B or D H G C is therefore necessary.

In accordance with the present invention, the breast grooving and heel seat concaving operations are performed first, the turning operation being performed last. In the first two operations the heel blank is held in any convenient manner and gaged from one of the flat side faces A E F B, D H G C.

The two operations referred to having been performed, the blank is placed in a turning machine and gaged again from the face A E F B or D H G C.

It is not necessary that the same lateral face A E F B or D H G C be used in all three operations provided the blanks run with a uniform dimension A D, since then gaging from either face is equivalent to gaging from the other.

Each of the three operations is thus gaged from what is actually or in effect the same flat side of the blank and the proper relation between the surfaces produced by them is assured.

The practice of this method is illustrated in the drawings. Fig. 1 shows the untreated blank. Fig. 2 illustrates the grooving operation as performed on a Cuban heel blank. The blank is clamped between two jaws 10—12, and its face A E F B is gaged by an adjustable gage 14 set by a screw 15. The gage 14 has, in this instance, a shoulder 16 gaging the face A B C D also. The blank thus held is passed relatively over the grooving cutter 18. The grooved blank is shown in Fig. 3.

Fig. 4 illustrates the concaving operation, in which the corresponding parts are numbered in the same way as in Fig. 2. Fig. 5 shows the concaved heel blank formed by this operation. Obviously either of the operations illustrated in Figs. 2 and 4 may be performed first.

The turning operation, which, according to the present invention, is the last of the three, is illustrated in Figs. 6 and 7. The turning machine, only those parts of which that are essential to an understanding of the present invention being shown, is of the ordinary type, except that it is provided with a gage 20 having integrally connected thereto a cam 22 by means of a bolt 23 and swing-

ing on a shaft 24 between operative and inoperative positions in which it is held by the pressure of a spring 26 on the faces 28, 30, respectively, of the cam 22. The gage is shown in operative position, and is thrown downward and backward when in inoperative position to permit the cutter 32 to trim the gaged side face, A E F B, of the blank. The blank is mounted in the machine as usual and its side face A E F B gaged against the gage 20, which is then moved to inoperative position, clear of the cutter-path.

A gage which is movable from operative position to permit treatment of the gaged face is claimed in my application Serial No. 274,583, filed May 2, 1928, and is not claimed herein.

Having thus described my invention, what I claim as new and desire to secure by Letters Patent of the United States is:

1. That improvement in methods of making wood heels which consists in first grooving a heel blank having a flat lateral surface, subsequently concaving the heel blank, and turning the rear and lateral surfaces of the heel blank after the concaving operation has been performed, the three said operations being gaged from the same flat lateral surface of the blank.

2. That improvement in methods of making wood heels which consists in gaging the heel blank from the same flat lateral surface in the grooving, concaving and turning operations.

3. That improvement in methods of making wood heels which consists in gaging the heel blank from a flat lateral surface in the grooving, concaving and turning operations.

4. That improvement in methods of making wood heels which consists in gaging a heel blank from the same flat lateral surface in two successive operations in different machines.

5. That improvement in methods of making wood heels which consists in gaging a heel blank in one machine from one of its flat lateral surfaces and then cutting a concavity in the heel seat surface of the heel blank, and then, in another machine, gaging the heel from the same surface in cutting the lateral and rear surfaces of the heel.

6. That improvement in methods of making wood heels which consists in placing a heel blank having a flat surface in a holder, gaging it therein from the said flat surface, performing a manufacturing operation on said blank while gaged in said holder, transferring the heel blank to a second holder, gaging it therein by the same said flat surface, and performing a second manufacturing operation on said blank while gaged in said second holder.

7. That improvement in methods of making wood heels which consists in making a heel blank adequate in size for the making of

one heel only, and having a flat face, and gaging the heel blank from the said flat face in two manufacturing operations in two different machines.

6 In testimony whereof I have signed my name to this specification.

ARTHUR F. COOK.
